UNITED STATES PATENT OFFICE.

LOUIS T. LAPAUGH AND ARTHUR R. LEIFF, OF UTICA, NEW YORK.

DESIGN FOR A PART FOR A PEDAL-CLIP.

SPECIFICATION forming part of Design No. 33,226, dated September 18, 1900.

Application filed August 22, 1900. Serial No. 27,734. Term of patent 7 years.

To all whom it may concern:

Be it known that we, LOUIS T. LAPAUGH and ARTHUR R. LEIFF, citizens of the United States, residing at Utica, in the county of Oneida and State of New York, have invented and produced a new and original Design for a Part of a Pedal-Clip for Bicycles, of which the following is a specification, reference being had to the accompanying drawings, forming a part thereof.

Figure 1 shows a perspective view of the clip part of our design. Fig 2 is a side elevation of the same. Fig. 3 is an end view as seen from the left of Fig. 2. Fig. 4 is an end view as seen from the right of Fig. 2. Fig. 5 is a plan view.

The feature of the design is the form or configuration of the clip part—that is to say,

having the flat plate-like body portion 1, the dependent plate-like part 2, having an oblong perforation 3 arranged at one end of the part 1, and the upwardly-turned portion 4, all relatively arranged, substantially as shown.

Having described our invention, what we claim as new, and desire to secure by Letters Patent, is—

The design for a part for a pedal-clip, as herein shown and described.

In testimony whereof we have signed our names to this specification in the presence of two subscribing witnesses.

LOUIS T. LAPAUGH.
A. R. LEIFF.
